UNITED STATES PATENT OFFICE.

ROBERT D. PIKE, OF SAN FRANCISCO, CALIFORNIA.

MULTIPLE-HEARTH CALCINING FURNACE.

Application filed November 19, 1923. Serial No. 675,448.

The hereinafter described invention relates in general to the construction of the principal combustion hearth of multiple calcining furnaces and more particularly to that type of calcining furnace wherein the combustion hearth is the lowermost one and in the region of which a very high temperature is carried due to the fact that all of the fuel is injected over said hearth. Where all of the fuel is burned immediately over the principal or lowermost hearth of the furnace, an intense flame will result with ultimate damage to the brick work or result in an overfiring of the material under treatment. To eliminate this difficulty, and at the same time to burn the necessary amount of fuel, I provide by the present invention control means for decreasing the air supply in the region immediately adjacent to the injected fuel, thereby cooling the flame at this point by reason of the consequent incomplete combustion, while arranging for the introduction of the balance of the air for combustion in a zone farther along the path of the flame. This latter air causes combustion of the combustible products which result from the initial incomplete combustion of the fuel and causes a secondary flame, which is long, not intense in its nature. At the same time I cause the air for the secondary combustion to pass through channels or passageways in the brick work which enclose the principal combustion chamber, which results in a cooling of the brick work and a prolonging of its life. To comprehend the invention, reference should be had to the accompanying sheet of drawings, wherein—

Fig. 1 is a broken vertical sectional elevation of the apparatus with my invention applied thereto.

Fig. 2 is a cross sectional plan view taken on the line 2—2, Fig. 1 of the drawings.

In the drawings the letter A is used to designate any suitably constructed calcining furnace which is provided centrally with a vertically disposed rotating column consisting of concentric spaced shells B and B'. The construction of the centrally disposed rotating column and the manner of regulating the flow of air into and through the rabble arms of the furnace is fully set forth in my Patent Number 1,506,942 concurrently filed herewith for Letters Patent on an improved ore roasting furnace.

Within the furnace structure is arranged a series of hearths disposed in superposed re-

lation, the lowermost hearth 1 being attached to the central column and rotating therewith while the rabble arms 2 associated with said hearth are thrust through the shell of the furnace structure and are stationary. All of the remaining hearths are attached to the stationary furnace shell and the rabble arms associated therewith are attached to and carried by the centrally disposed rotating column. Of the series of superposed hearths with which are associated the rabble arms 4, the lowermost one of the series and which is designated as 3' is the one through the opening 5 of which the material undergoing treatment drops onto the bottom hearth 1 and is rabbled outwardly over said hearth until discharged through an annular opening 6 into an annular trough 7 wherein scrapers attached to the revolving hearth 1 carry the calcined material around until it is dropped through a discharge opening 9. A circular seal curtain 10 which is secured to and depends from the under face of the hearth 1 rotates or moves within a seal pot 11, which, like the annular trough 7, is integral with the furnace shell and this seal pot 11 is filled with dust or similar material to prevent the flow or escape of air or gas to or from the interior of the furnace. Air for maintaining cool the rabble arms 2, is introduced therein through an air supply pipe 12 and which air after effecting the cooling of the rabble arms by a circulation therethrough, escapes therefrom through the outlet duct 13, the air inlet pipe 12 being attached or held to the stationary rabble arms 2 by a bracket 14 secured to the furnace shell.

Air for combustion enters the furnace structure through the air inlet duct 15 and passes therefrom into the annular passageway 16, which completely surrounds the space between the lowermost hearth 1 and the hearth 3' next immediately above, which space is commonly known as the primary combustion chamber. The annular passageway 16 is separated from the primary combustion chamber by a curtain wall 17 and from the furnace shell by the insulated lining 18. Suitable burners 19 adapted to convey liquid, pulverized or gaseous fuels, are thrust through the furnace shell and the insulated lining 18, preferably at three points and in a semi-tangential direction with reference to the furnace shell. These burners discharge into the combustion chamber

through the ports or openings 20, which establish communication between the annular passage 16 and the interior of the furnace. If all of the air necessary or required for complete combustion is taken into the openings 20 and which in reality constitute somewhat small mixing chambers, a very hot and intense flame will result.

Passages 21 communicate the annular space 16 with radial passages 22 formed in the brick work of the hearth 3' next above the bottom hearth 1, and the size or area of these passageways may be regulated by damper tiles 24, each of said tiles being accessible from the outside of the furnace structure through doors 25. The air passing through the passages 22' of the hearth 3' enters the furnace or rather the primary combustion chamber, through the ports 23, where the said air mixes with the combustible gases, causing or producing a long flame to pass upwardly through the furnace. It will be understood that the size of the passages for the air through the hearth 3' should have a sufficient area in relation to the size of the openings 20 that at least one-third of the total air for combustion may enter through the ports 23 into the primary combustion chamber.

30 By manipulation of the tiles 24, from entirely shut to entirely open, the flame can be changed from a short and intensely hot one to a longer, less intensely hot and with a secondary combustion in ports 5, which 35 will project a long flame further up into the furnace.

While I have described the invention in its preferred embodiment, I do not wish to be understood as limiting or restricting the invention to the details of construction herein shown and described, but on the contrary wish to be understood as claiming the invention as broadly as the state of the art will warrant.

45 I claim—

1. In a multiple hearth mechanically rabbed furnace, a primary combustion chamber therein bounded top and bottom by two successive hearths, radially disposed air passages formed through the upper hearth and communicating at their inner end portions with the combustion chamber, an annular air passageway surrounding the combustion chamber and in communication with the air 55 passages of the upper hearth, means for regulating the flow of air from the said annular passageway into and through the radially disposed air passages of said hearth, fuel burners associated with the combustion 60 chamber, and means for admitting air from the annular air passageway into the combustion chamber for supporting combustion therein.

2. In a multiple hearth mechanically rabbed furnace, a combustion chamber bound-

ed top and bottom by two successive hearths and surrounded by a curtain wall spaced from the inner wall of the furnace and co-acting therewith to form a vertically extended annular air passageway, a series of 70 radially extended air passages formed through the said upper hearth and communicating at their outer ends with the said annular passageway and at their inner end with the combustion chamber, means 75 for regulating the flow of air from said annular passageway into and through the said radially disposed air passages, and fuel burners associated with the combustion chamber of the furnace.

3. In multiple hearth mechanically rabbed furnace, a combustion chamber therein bounded top and bottom by two successive hearths, the upper of which is provided with a series of radially extended air passages communicating at their inner ends with the combustion chamber, means for admitting air through said air passages into the combustion chamber and fuel burners associated with the said combustion chamber.

4. In a multiple hearth mechanically rabbed furnace, a primary combustion chamber therein bounded top and bottom by two successive hearths, radially disposed air passages formed through the upper hearth and communicating at their inner end portions with the combustion chamber, an annular air passageway surrounding the combustion chamber and in communication with the air passages of the upper hearth, fuel burners associated with the combustion chamber, and means for admitting air from the annular air passageway into the combustion chamber for supporting combustion therein.

5. In a multiple hearth mechanically rabbed furnace, a combustion chamber bounded top and bottom by two successive hearths and surrounded by a curtain wall spaced from the inner wall of the furnace and co-acting therewith to form a vertically extended annular air passageway, a series of radially extended air passages formed through the said upper hearth and communicating at their outer ends with the said annular passageway and at their inner ends with the combustion chamber, and fuel burners associated with the combustion chamber of the furnace.

6. In a multiple hearth mechanically rabbed calcining furnace, a stationary upper hearth, a rotating bottom hearth, stationary rabbling mechanism superimposed over said bottom hearth for agitating the material carried by the hearth and for gradually causing a movement thereof toward the periphery of the hearth, means for projecting a calcining flame over said bottom hearth in a plane substantially parallel with

- its upper surface and at points between the rabbling mechanism for acting on the material as conveyed by said hearth between said rabbling mechanism, an annular trough 5 for receiving the material from the hearth, and provided with the discharge opening, and means operating in the trough for moving the material therein to discharge through said opening.
- 10 7. A calcining furnace including a stationary upper hearth and a rotating bottom hearth, stationary rabbling mechanism extending over the bottom hearth for conveying the material thereon toward the periphery of the hearth, means for projecting a calcining flame over said bottom hearth in a plane substantially parallel with its upper surface and at points between the rabbling mechanism for acting on the material 15 as conveyed by said hearth between said rabbling mechanism, an annular trough beneath the bottom hearth for receiving the material therefrom, and provided with an outlet, scraper blades movable with the bottom hearth within said trough for conveying the material received therein to said dis-
- charge opening, a sealing trough beneath said hearth and disposed concentrically of said first mentioned trough, a sealing medium therein, and means depending from the 30 hearth and projecting into said sealing medium.
8. In a calcining furnace, a plurality of stationary upper hearths and a rotating bottom hearth, stationary rabbling mechanism 35 superimposed over the bottom hearth; means for injecting a calcining flame tangentially over the bottom hearth in a plane substantially parallel with the upper surface of the hearth and at points between the rabbling mechanism for acting on the material as conveyed between said rabbling mechanism, means for receiving the material as discharged peripherally of the hearth, an 40 annular sealing trough beneath the hearth, 45 an annular curtain depending from the hearth, and a sealing medium within the trough through which said curtain moves.

In testimony whereof I have signed my name to this specification.

ROBERT D. PIKE.
